UNITED STATES PATENT OFFICE.

GEORGE S. CLAPPER, OF VALPARAISO, INDIANA.

FOLDING POULTRY CRATE.

Application filed December 16, 1922. Serial No. 607,398.

To all whom it may concern:

Be it known that I, GEORGE S. CLAPPER, a citizen of the United States, residing at Valparaiso, in the county of Porter and 5 State of Indiana, have invented certain new and useful Improvements in Folding Poultry Crates, of which the following is a specification.

My invention relates to improvements in 10 folding poultry crates, and it more especially consists of the features hereinafter pointed out in the annexed claims.

The purpose of my invention is to provide 15 a folding poultry crate that is simple in construction; that is free from the defects and complexity of folding crates as heretofore used; that by means of very simple expedients forms a very rigid crate when opened and a compact crate when closed; 20 that provides means for dividing the crate into two sections when desired so as to prevent the crowding of poultry to either end of the crate; that by reason of a two compartment crate the smothering of poultry 25 is prevented which has heretofore caused considerable loss to shippers; and that by reason of a hinged partition it is possible to quickly divide the crate into two sections or leave it in a single section as desired.

With these and other ends in view, I illustrate 30 in the accompanying drawings such instances of adaptation as will disclose the broad underlying features without limiting myself to the specific details shown thereon and described herein.

Figure 1 is an elevation in cross section looking toward one end of an open crate ready to receive poultry.

Fig. 2 is a similar view with the sides, 40 ends, and top or cover of the crate folded together on the base.

Fig. 3 is a lengthwise elevation partly in section.

Fig. 4 is a top plan view of an opened 45 crate.

Fig. 5 is an enlarged section of one of the end members of the crate.

Fig. 6 is a plan view of one of the partition catches.

Fig. 7 is an elevation partly in section of 50 the cover clamping means.

Fig. 8 is a plan view of Fig. 7 also partly in section.

In practically carrying out my invention, 55 I may use any suitable base 1 which may be formed of slats or boards constituting a con-

tinuous bottom. It has end cross cleats 2 on the under side and other cross cleats 3 located between the ends. These serve to stiffen the base. At each end of the base 60 1, there are hinged end sections 4 adapted to fold over flatwise onto the base when the crate is folded for return shipment. These end sections are formed of slats or battens that are reinforced by upright battens 5. 65 In addition to the uprights 5, rods 6, as shown in Fig. 1 are also secured to the battens. These rods terminate in threaded upper ends 9. They cooperate with clamping plates 10 and thumb nuts 8 to hold the 70 hinged covers 22 and 23 assembled on the end sections 4. The end sections 4 are hinged to the base 1 by hinges 7, as shown in Figs. 1 and 3.

The front section 16 is also formed of slats 75 that are reinforced by vertical cross pieces or uprights 18 and the rear section 15 is similarly made with upright reinforcement 17. In addition to these reinforcements, a pair of strips 27 are secured on the inside 80 of sections 15 and 16 at both ends thereof, forming a groove between each pair, and other similar strips 29 are attached to the under side of the cover sections 22 and 23. These strips 27 and 29 are spaced apart so 85 as to hold the end sections 4 in position when the crate is opened. The lower members 30 of end sections 4 are made somewhat thicker than the upper slats and may be mortised to receive the uprights 5, as shown 90 in Fig. 3, and the upper slats of the end sections may be pieced out on each side of the uprights 5 if desired to fill the groove formed between a pair of guide strips 29.

Along the rear edge of the base 1 the 95 piece 13 is fastened to it so as to extend the full length of the base, and along the front edge a similar piece 14 is fastened to the base but this latter piece is not as wide as the former which is made wider to raise 100 the pivot portion of the hinges 19 higher than the pivot portion of the hinges 20. By reason of this difference the front section 16 and cover portion 22 may be flattened as shown in Fig. 2, on the folded-in end 105 pieces, and the rear section 15 with a cover portion 23 will lie flat on top of the front section and its cover portion. The front section 16 and its cover portion 22 are secured to each other by hinges 26, and the 110 rear section 15 with its cover portion 23 are similarly secured to each other by hinges 25.

The hinges 25 and 26 are secured to the respective portions of the crate opposite the reinforcements 17 and 18 and the cover reinforcements 38.

5 The two cover portions 22 and 23 formed of battens 37 are held in place on the end sections 4 by means of clamps 10. These clamps have beveled ends 11 which serve to draw the adjacent slats of the cover portions toward each other and at the same time, by reason of the thumb nut 8, serve to hold the ends of the cover tightly and securely on the end sections 4. Beneath the clamping plate 10 and surrounding the 10 threaded portion 9 coil springs 12 are placed. These serve to raise the clamping plates 10 when the thumb nuts 8 are turned to loosen the clamps. Sufficient clearance for the springs 12 is formed in the adjacent 15 edges of the cover battens which are found under the clamping plates. At the center of the cover portions a hinged hasp 28 is placed. This serves to hold cover portions 22 and 23 together and it may be secured 20 in any well known way. This hasp when the crate is folded as shown in Fig. 2 cooperates with a swiveled eye 32 which projects from the strip 14 thereby holding the 25 parts of the crate in folded shape for re- turn shipment. In addition hooks 33 se- 30 cured to cover portion 23 as shown in Figs. 1 and 2 are adapted to engage eyes 34 secured to the base 1 and thus hold the ends of the 35 folded crate securely to the base. A hinged door 24 is placed in the cover portion 23 as shown in Fig. 6. It is held in place by well known turn buttons.

The crate is divided into two sections by means of a partition 35 formed of wire netting. It is secured to the base 1 by means 40 of hinges 36. The partition 35 is held in a raised position by a pair of catches 39 pivoted on pivot pin 40. The catches have notches formed on the under side so as to hook over the upper edge of the partition. A coil spring 41 encircles the pivot pin 40 and serves to keep the catch in an engaging 45 position. A stop 42 prevents the spring 41 from moving the catch too far and a turn 50 button 43 serves to lock the catches 39 in place. When the partition 35 is not in use it will lie flat on the base or floor 1 of the crate without interfering with an end section that will fold over it.

55 In order that the end portions of the front and rear sections may be held against springing open, flat hinges 31 are placed in line with hinges 25 and 26 and flat hinges 21 are placed at the ends in line with hinges 19 and 20. The lower member of the flat 60 hinges 21 is formed in the shape of a brace as shown in Fig. 1 so as to stiffen this portion of the crate. One end of each hinge 19 and 20 passes through the door 1 and cross battens 3, where they are bent at

about right angles to be secured under the cross battens. This construction makes the crate very strong so as to withstand the rough uses to which crates of this kind are subjected in transit. If desired small 70 blocks 44 may be placed at each end of the cover portion 23 near the rear edge thereof so as to equalize the height at this portion of the crate to approximately correspond to the projection 9 of the clamping bolts 6. 75 This however, is optional and may or may not be used. In some cases the presence of such blocks may assist in the more even stacking of filled crates.

In filling the crate the door 24 is opened 80 on its hinges in the usual way. If the crate is divided into two compartments by means of the partition 35, one compartment can be filled through the door 24 and then the partition 35 can be swung toward the filled 85 compartment while the other compartment is being filled. In this way the first compartment remains closed by the partition (shown in dotted lines of Fig. 3) so that poultry cannot escape while the other compartment is being filled. When the crate is completely filled the door 24 is closed and the partition 35 is locked by the catches 39 and turn buttons 43.

90 What I claim is:

1. In folding crates, a suitable base, ends hinged to the base, sides also hinged to the base, a two-part cover in hinged relation to the sides, and means for attachably and detachably holding the cover parts against separation and at the same time positively draw them against the ends so as to hold the parts firmly assembled against collapse while the crate is in active service.

100 2. A poultry crate, adapted to have its sides, ends and two-part cover folded on the base for re-shipment, a partition foldable on the base adapted to stand vertical when the crate is open dividing the crate into separate compartments, a door within one of the cover parts adapted to give access simultaneously or separately to both compartments and means adapted to draw the cover parts toward each other and also positively draw them against the ends said means serving to hold the parts in assembled relation when the crate is unfolded.

110 3. In folding crates, a base, sides foldable thereon, hinges connecting the sides to the base said hinges being differentially off-set with respect to the two sides so that the sides fold over each other on different planes, and a right angle extension to the hinges passing through the base and being fastened on the under side thereof.

120 4. In crates, a base, ends therefor pivoted to fold against the base, a front and back foldable over the ends, and hinges therefor arranged in two groups one group for the back and the other group for the front said

hinges having their pivotal points on different planes so as to admit of the front and back being folded against each other the lower half of each hinge being secured 5 on the under side of the bottom.

5. In crates, a base, suitable ends, a fastening bolt secured to the end projecting above the same in a threaded portion, a flanged clamping plate on the threaded portion, a thumb nut above the clamping plate, and a spring between the plate and the 10 upper edge of the crate end.

6. In crates, a base, ends and sides therefor, a two part hinged cover thereon, fastening bolts projecting from the ends above and between the two parts of the cover, clamping plates on the bolts, beveled flanges formed 15 on the plates adapted to draw the two parts of the cover toward each other, clamping nuts above the plates, and springs beneath 20 said plates adapted to raise the same when the nuts are released.

7. In crates, a base, ends and sides therefor, a two-part hinged cover thereon, fastening bolts engaging the ends and extending 25 above the same between the two parts of the cover, clamping plates on the bolts, beveled flanges formed on the plates adapted to

draw the two parts of the cover toward each other, cooperating clamping nuts on the 30 bolts, and springs beneath the said plates adapted to raise them when the nuts are released.

8. In crates, a base, ends and sides therefor, a two-part hinged cover thereon, fastening means engaging the ends and located between the two parts of the cover, clamping plates on such means, means on the plates adapted to draw the two parts of the cover toward each other when pressure is applied 35 from one side of said plates, and elastic means operating on the other side of the plates adapted to move the same when pressure is released therefrom.

9. In crates, a base, ends and sides therefor, a two-part hinged cover thereon, fastening bolts engaging the ends positioned between the two parts of the cover, and clamping means on the bolts adapted to hold the two parts of the cover against separation 40 and at the same time draw them toward and positively hold them in engagement with the ends in a detachable manner while the crate is in service.

In testimony whereof I affix my signature.
GEORGE S. CLAPPER.
